UNITED STATES PATENT OFFICE.

CLARENCE DOUGLAS BROWN, OF BAY SIDE, NEW YORK.

CLOTHES DRIER.

Application filed May 25, 1925. Serial No. 32,570.

This invention relates to household articles and has particular reference to driers for towels, cloths, garments, or various analogous articles.

Among the objects of the invention is to provide an indoor clothes drier of the most compact construction and yet with large drying capacity and one that is so foldable or collapsible as to not only render it adapted to occupy the least amount of space, but moreover to possess facilities for an aesthetic or ornamental effect.

More specifically, an object of the invention is to provide a relatively shallow or flat box-like construction adapted to be supported or fixed in any convenient elevated position as against a vertical wall, the same including a lid or cover having at its front or outer surface a plain space for the application of ornamentation such as a painting, a motto, or some other means of decoration.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a front perspective view showing the drier open and in operative position.

Fig. 2 is a vertical transverse section of the same on the line 2—2 of Fig. 1, but with the line omitted and the bracket brace in idle position for the sake of clearness.

Fig. 3 is a horizontal section with the device collapsed, on the line 3—3 of Fig. 1.

Fig. 4 is a front elevation with the cover lifted and showing particularly the manner of nesting of the brackets, the line being omitted.

Referring now more specifically to the drawings I show my construction as comprising a shallow box or casing having a vertical bottom or rear wall 10, top and bottom walls 11 and 12, end walls 13, and a cover or front panel 14 hinged at its upper edge at 15 to the top panel 11. This casing may be secured in any well known manner to the vertical wall of a building either by means passing through the rear panel 10 or by means of hangers 16 ex-

tending upward at the top and adapted to co-operate with nails, screws, hooks, or the like.

Mounted within the casing as by means of vertical pivot rods 17 and 18 are a pair of brackets 19 and 20 respectively. Each of these brackets is of generally triangular formation, one including a horizontal upper leg 19^a and an inclined lower leg 19^b, while the other bracket has similar upper and lower legs 20^a and 20^b. The rear ends of these two legs have pivotal co-operation with the axis pins 21 of the pivot rods. These brackets and other features are practically similar to each other and in folded or collapsed position they lie in approximately the same plane, portions of the legs being so twisted or formed as to nest closely with one another within the casing, as shown best in Fig. 3. Fig. 1 also shows in dotted lines the folded or nested position of the bracket 20. These brackets may be made of any suitable material but shown as of flat bar metal.

The upper leg of each bracket is so formed as to present a relatively flat face toward the cover 14 when the device is open and this face may be provided with a series of holes or pits 22 or any other analogous arrangement for co-operation with a brace 23 carried preferably by the inside of the cover panel 14 and adapted to swing inward in closed position and outward in operative position, the outer or free end of the brace co-operating with any selected one of the holes or pits 22 to lock the standards in spread apart position, the cover at this time lying more or less closely upon the upper edges of the upper legs of the standards.

The lower leg of each standard as well as the apex portion thereof is provided with a series of holes 24 through all of which, beginning with one end hole of one bracket, a flexible line such as a cord 25 is laced, preferably in parallel strands as shown in Fig. 1. With the ends of the cord suitably fastened, as by knotting, the intermediate portions of the cord will adjust themselves as to tautness when the casing is opened and the brackets are swung outward from each other to the position shown in Fig. 1. In this position the braces 23 will be swung around their pivots into interlocking engagement with the upper legs of the brackets as specified, holding the several runs of the cord not only taut, but properly spaced

in vertical planes from one another so as to give a large amount of space for aeration and drying. When the device is not to be used as a drier the braces are swung around 5 to the inside of the cover panel 14 and the brackets are folded inward as shown in Fig. 3, the cord folded within the casing in a natural way. The cover panel then drops down to closed position and is capable 10 of ornamentation to simulate an ornamental device such as a picture or the like.

I claim:

1. The herein described drier comprising, in combination, a casing having a hinged 15 cover, line-supporting means mounted within the casing and movable therefrom, a flexible line supported on said means, said

line supporting means being movable into position to stretch the line, and bracing means carried by the cover and co-operating with the line-supporting means while in operative position to hold the line taut. 20

2. Mechanism as set forth in claim 1 in which the line supporting means is pivoted in the casing and swings outward therefrom 25 around a vertical axis.

3. Mechanism as set forth in claim 1 in which the line supporting means consists of two brackets mounted on vertical axes within the ends of the casing and adapted to 30 swing outward therefrom away from each other.

In testimony whereof I affix my signature.
CLARENCE DOUGLAS BROWN.
